ADVERTISING SIGN OR SIMILAR ARTICLE

Edwin G. Cole, Chicago, Ill., assignor to Swift & Company, Chicago, Ill., a corporation of Illinois

Filed Oct. 24, 1962, Ser. No. 72,247

Term of patent 14 years

(Cl. D1—12)

The broken-line representation of familiar scenes, maps and advertising matter is for purposes of illustration only.

I claim:
The ornamental design for an advertising sign or similar article, substantially as shown and described.
